Inventor:
J. G. Hunt

UNITED STATES PATENT OFFICE.

JAS. G. HUNT, OF READING, OHIO.

PORTABLE FIELD-FENCE.

Specification forming part of Letters Patent No. 16,236, dated December 16, 1856; Reissued June 30, 1857, No. 474.

To all whom it may concern:

Be it known that I, JAMES G. HUNT, of Reading, in the county of Hamilton and State of Ohio, have invented new and useful Improvements in the Construction of Portable Farm-Fences; and I do hereby declare that the following is a full, exact, and complete description of the same, reference being had to the accompanying drawings, 10 making part of this specification, like letters referring to like parts.

The nature of my invention consists in the construction of a fence, composed of sections or panels, that can be taken down and 15 put up at pleasure, without a great amount of labor, or waste of material.

Figure 1, is a longitudinal view of the fence, showing two panels, and the manner of joining them. Figs. 2 and 3, are 20 cross sections, showing the foot pieces, and the manner of bracing the fence. Fig. 4, is the longitudinal section of a joint.

In constructing this fence, I first take four boards or bars, say ten feet long, four 25 or five inches wide, and one inch thick, as seen at A¹, A², A³, A⁵, Figs. 1, 2 and 3. These bars are placed at suitable distances from each other, the three lower ones, say four or five inches apart, and the top bar 30 A⁵, a distance of four or five feet from the bottom of the bar A¹, or equal to the height of the fence. Near each end of these, and upon each side, are placed slats, or upright pieces, in length equaling the height of the 35 fence. These slats are seen at B, B, &c., in Figs. 1, 2 3 and 4. These slats are nailed to the bars A¹ A², A³, and A⁵, as represented. Two slats are placed in the middle, as seen at C, and secured in a similar manner, there 40 being one upon each side. Between the bars A³, and A⁵, is placed the bar A⁴, which extends some 12 or 15 inches beyond the slats B, B, as seen at D, D, Figs. 1 and 4. Where the bars A⁴, A⁴, pass between the slats C, 45 they are secured by a nail or pin. This constitutes a panel ready for setting up. For a fence designed simply to turn cattle (oxen, cows, &c.) the bars A¹, and A², may be omitted, thus allowing smaller animals as 50 sheep and swine, to pass from one inclosure to another, while larger animals would be restrained.

If it is desirable to make the panels of a more ornamental character, the bars A²,

A³ and A⁵ may be omitted, and upright 55 pickets nailed to the bars A¹ and A⁴. In either case, the bar A⁴, is inclined an amount equal to its own width, within the length of every panel, for purposes hereinafter described. A sufficient number of these panels being made to inclose a field of given dimensions, they are to be distributed along the line of the fence, to be ready for use.

For the purpose of making a secure foundation, a stone or block of wood may be used 60 as seen at E, E, E, &c. If the ground is not exactly level, one block may be raised to suit the opposite one. I next take a sill F, which is formed of a piece of timber, say 1½ inches thick, and from four to six feet long. 70 This is notched in the middle upon the upper side as seen at G, Fig. 5, the end of the bar A¹ being also notched as at H, Fig. 5, the ends of the two bars meeting at the center of the sill G.

The fence is supported in an upright position, by means of braces I, I, seen in Figs. 2 and 3, and in section at I Fig. 4. The braces are also represented in detached section, Figs. 2 and 3. The upper end of these 80 are notched as seen in the figures, so as to form a lock, both upon the upper and under sides or edges of the bars A⁴ and A⁵, as seen at K K Figs. 2 and 3. The lower end of these braces are nailed or pinned upon 85 opposite sides of the sill F. In putting the panels together after these several preparations, the sills F, are placed upon their supports, and adjusted to a horizontal position, the two ends of a panel are then brought 90 together, and the bars A⁴ A⁴, (which are depressed at one end exactly their own width, as shown in Fig. 1,) are passed between the slats B, B, until the two ends of the bars A¹, A¹, meet in the center of the notch in 95 the sill as seen at G, in Fig. 5. The upper ends of the braces are then adjusted so as to fit the bars as represented at K, K. The two panels are then secured by a pin or nail passing through the bars A⁴ at L, L, 100 Figs. 1 and 4, thus preventing their separation. The foot of the braces are secured to the sill by a nail as above described, and the sill fastened in like manner to the block E.

In turning a corner or right angle, one of the long bars A⁴, passes between two slats with which a panel is provided for that

purpose as seen at M, M, Fig. 1, and immediately above or below the corresponding bar A⁴, in the panel standing at right angles thereto, as seen at N, Fig. 1. The 5 lower section of the panel is secured by means of a short bar, introduced between the bars A¹ and A², the end of which is seen at O, Fig. 1. An extra pair of slats can also be added as seen at P, Fig. 1 to one 10 or both of which hinges for the hanging of a gate, can be attached as seen at R, R. By having the holes bored where the nails or pins enter the foot of the braces, at S, S, and also at L, L, N and O, this fence can 15 be taken apart removed and put up again without inconvenience, loss of material or the loss of time. If, for the purposes of strength and durability, or for the sake of appearance, it is desirable, a board may be 20 nailed flatwise upon the top of the fence, as represented in the figures at T, so as also to protect all the exposed ends of the timber.

In addition to the foregoing means of 25 bracing and securing the fence, from a lateral movement, I also strengthen the mid-

dle of the panels by introducing an extra set of slats, U, Fig. 1, a slat being placed upon each side of the bars, and secured by nails or pins. The fence may be rendered still more secure, by using braces like those 30 seen in Figs. 2 and 3, resting directly upon the ground or upon blocks as do the other braces. It will be observed, that braces constructed in this manner are adjustable to any part of the fence, and applicable to 35 any height, and operate at the same time, as a tie, to bind the fence to the ground, as seen at K.

I claim—

The compound triangular brace as shown 40 and described for the uses and purposes set forth in combination with the projection of one or more rails in whole part of one section or panel beyond the slats or battens and between the slats or battens of the 45 adjoining panel.

JAS. G. HUNT.
